(57) **CLAIM**

The ornamental design for eyewear as shown and described.

DESCRIPTION

FIG. 1 is a front, left side and top perspective view of eyewear, showing our new design, with the front, right side and top perspective view being a mirror image thereof; FIG. 2 is a front and right side perspective view thereof; FIG. 3 is a right side view thereof; FIG. 4 is a rear view thereof; and,

FIG. 5 is a front view thereof, with the temples in a folded position.

The Bling2O logo shown on the upper right side of the lens portion forms no part of the claimed design.
